HAND HELD FLEXIBLE SCRAPER

Dana Peterson, P.O. Box 2141, San Diego, Calif.

Filed Jan. 22, 1964, Ser. No. 78,319

Term of patent 14 years

(Cl. D9—6)

FIG. 1 is a perspective view of a hand held flexible scraper, showing my new design;
FIG. 2 is a front elevational view thereof;
FIG. 3 is a rear elevational view thereof;
FIG. 4 is a side elevational view thereof; and
FIG. 5 is a modified form of the design shown in FIGS. 1 to 4, inclusive.

I claim:

The ornamental design for a hand held flexible scraper, as shown.
